UNITED STATES PATENT OFFICE.

HARRY L. JOHNSON, OF JAMAICA PLAIN, MASSACHUSETTS, ASSIGNOR TO PERCY E. GINN, OF BOSTON, MASSACHUSETTS.

WAX-WRAPPING MACHINE.

Application filed April 13, 1922. Serial No. 552,151.

To all whom it may concern:

Be it known that I, HARRY L. JOHNSON, a citizen of the United States, and resident of Jamaica Plain, county of Suffolk, State of Massachusetts, have invented an Improvement in Wax-Wrapping Machines, of which the following description, in connection with the accompanying drawing, is a specification, like characters on the drawing representing like parts.

This invention relates to machines designed to wrap a sheet of paper or other wrapper about a package or carton, and it relates particularly to the means for conveying the cartons or packages through the machine and past the wrapping devices.

The objects of the invention are to provide an improved package-conveying means which is constructed to firmly hold the package in position during its movement past the wrapping mechanism, and otherwise to improve the conveying mechanism of wrapping machines all as will be more fully hereinafter set forth.

In order to give an understanding of the invention I have illustrated in the drawings a selected embodiment thereof which will now be described after which the novel features will be pointed out in the appended claims.

Fig. 1 of the drawings is a fragmentary view of the package-conveyer having my improvement applied thereto.

Fig. 2 is an enlarged view showing the position of the parts as each package is delivered to the conveyer.

Fig. 3 is a view similar to Fig. 2 showing the position of the parts at a short interval of time prior to that in which they assumed the position shown in Fig. 2.

The mechanism herein shown is designed to be used in connection with a wrapping machine having the construction illustrated in my co-pending application Ser. No. 314,592, filed August 1, 1919.

The machine shown in said application comprises a belt for bringing the packages to be wrapped into the machine, a table or plate having an opening of a size to receive the packages, means to deliver wrappers in position over the opening, means to force individual packages through said opening thereby to fold a wrapper partially thereabout, end folders for folding the ends of each wrapper and a package conveyer for

taking packages after they have been moved through said opening and carrying said packages past the end folders, which operate to fold the ends of the wrapper against the package.

In order that the wrapping operation may be satisfactorily performed it is desirable that after the wrapper has been folded about the package by applying the package through the opening in the table, said wrapper should be held firmly against the sides of the packages while the conveyer is carrying the partially wrapped package past the end folders, for if during this latter operation the wrapper is loosened from the package or bulges out from the sides thereof the wrapper will be loose on the package when the wrapping is completed.

My present improvement provides means for holding the wrapper tightly against the sides of the package while the latter is being moved by the conveyer past the end-folding devices so that when the end folders operate on the ends of the wrapper the portions thereof which engage the sides of the package will be held wrapped tightly about the package.

Inasmuch as my present invention relates simply to the conveying mechanism I have only shown herein a sufficient portion of the wrapping machine to enable the invention to be understood.

In the drawings 1 indicates a portion of the frame which supports the operating mechanism and 2 indicates in cross section the feeding-in belt which conveys the packages into the machine.

As the packages are carried along by the conveyer 2 they are acted on by a reciprocating transerrer 3 which transfers them from the conveyer 2 onto a vertically-moving elevator 4, said elevator takes the individual packages and forces them upwardly through an opening 5 formed in a table 6. The wrappers are fed into position across the opening 5 and beneath the table 6 by mechanism such as illustrated in my above-mentioned application so that during the upward movement of the elevator 4 the package 8 is carried against the wrapper, and the package 8 and wrapper are forced up through the opening 5 thus folding the wrapper about the body of the package 8. When the package is fully elevated as shown in Fig. 2, a reciprocating folder 7

2

moves forwardly to tuck the edge of the wrapper underneath the package 8, as shown in Fig. 2. The package at this time with the wrapper folded about the body thereof and with the ends of the wrapper projecting beyond the body, as shown in Fig. 4, is then taken by the package conveyer and moved over the table 6 to the end-folding devices 75 which fold the ends 9 of the wrapper about the package. As stated above the present invention relates to the construction of the package conveyer and has for its object to provide a novel conveyer arranged so that the wrapper 10 will be held tightly wrapped about the body of the package while the latter is being conveyed to the end folding devices.

The package conveyer comprises an endless belt or chain 11 passing around sprocket wheels 12 and 13 carried by the frame and one of which is positively driven, and a plurality of pushers 14 secured to the chain 11 at intervals, said pushers operating to take the individual packages as they are delivered through the opening 5 by the elevator 4 and feed them past the end-folding devices, (not shown) and toward the left in Fig. 1.

In order to hold the wrappers 10 closely wrapped about the body of the package while they are being acted upon by the pushers 14 I provide a clamping member 15 which is associated with each pusher and which engages the opposite side of the package 8 from that which is engaged by the pusher so that while the package is being conveyed by the conveyer it will be firmly held between the pusher and the clamping member 15. Each pusher is secured to a block 16 connected to a link of the chain and the clamping members 15 are pivotally connected to the block 16, as shown at 17. Means are provided for swinging each clamping member up out of the way while the corresponding pusher is approaching the package 8 that is being elevated through the opening 5 so as to allow the clamping member to pass over the package, and as soon as the pusher has engaged the package the clamping member is swung down into engagement with the opposite side.

To accomplish this each clamping member is provided with an arm 18 carrying a roll 19 which is adapted to engage a cam member 20 fast to the frame and located over the opening 5. This cam member 20 has the two inclined faces 21, 22 and the construction is such that as the pusher approaches the package 8 being elevated through the opening 5 as shown in Fig. 3, the roll 19 engages the cam face 21 thereby swinging the clamping member upwardly into a horizontal position above the package, in which position it does not interfere with the movement of the package through the opening

5. The clamping member is held in this position until it has been carried over the package 8 and the pusher is about to engage the package, at which time the roll 19 passes down the inclined face 22 thus allowing the clamping face to swing downwardly against the package under the influence of the spring 23. By the time the pusher has engaged the package the roll 19 is passed off from the inclined face 22 and the package is firmly held between the pusher and the clamping member and continues so held while it is fed along past the end folders, not shown.

In order to still further assist in wrapping the wrapper 10 closely about the body of the package I provide a stationary guide member 24 against which one face of the package engages as it is carried upwardly by the elevator 4 and said guiding member has an arm 25 extending laterally therefrom which is situated to engage the top of the package when the elevator 4 is at the upper end of its stroke, as seen in Fig. 2.

26 is a pivotally mounted finger adapted to engage one side face of the package as the latter is elevated by the elevator 4 and with this construction the package will be firmly held between the guide 24 and finger 26 while it is being raised and when it is in position to be engaged by the pusher 4 the wrapper will be held closely to the sides of the package by said guide 24, the arm 25 and pivoted finger 26.

The clamping member 15 is preferably provided with a laterally-extending finger 27 adapted to engage the top of the package when the clamping member assumes its operative position, and, therefore, as soon as the pusher 4 engages the package the wrapper will still continue to be tightly held against the body of the package by the pusher, the finger 27 and the clamping member 15.

As the package is moved to the left Fig. 1 by the conveyer the finger 26 swings backwardly and the edge of the wrapper is folded under the package during the movement of the latter.

By this means the wrapper is held firmly folded about the package while it is being conveyed to and past the end folders 75 by the conveyer so that when the end folders, which are not herein shown, as they form no part of the present invention, operate on the ends of the wrapper to fold the latter about the ends of the package 8, the portion of the wrapper surrounding the body of the package will be held firmly in contact therewith and a tightly wrapped package will result.

After the package has been completely wrapped it is delivered to a pair of endless belt devices, one of which is shown at 28, which take the packages and discharge them

from the conveyer. When the package is being acted on by the endless belt devices 28 the clamping member is removed from engagement with the package so as not to interfere with the discharge of the package from the conveyer and this is accomplished by a cam member 29 constructed similarly to the cam member 20 and arranged to swing each clamping member into horizontal position thereby releasing the package so that it can be removed from the conveyer by the endless belt devices 28.

The finger 27 is adjustably mounted on the clamping device to provide for operating on packages of different sizes and the arm 25 is also adjustably secured to the guide 24 for the same purpose. Similarly the clamping member 15 can be adjusted toward and from the pusher to accommodate different sizes of packages and this is provided for by pivoting the clamping member to a slide 30 which in turn is adjustably secured to the block 16.

I claim.

1. In a wrapping machine, the combination with a support on which the packages to be wrapped are supported, of an endless carrier having one run above and parallel to said support and situated above the packages supported thereon, pushers mounted on said carrier and arranged to depend from said run thereof, means to deliver packages singly into position to be engaged by the pushers, the latter operating to move the packages over the support, a clamping member associated with each pusher and adapted to engage the front side of the package engaged by said pusher, each clamping member being mounted to swing about a horizontal axis, and means to swing each clamping member into position to clear a package which has just been delivered to said support and while the corresponding pusher is being brought into operative engagement with said package, and then swing said clamping member into position to clamp said package to the pusher as the latter engages the package to move it forward.

2. In a wrapping machine comprising means to support packages to be wrapped, an endless chain element having one run operating above said support, pushers carried by said element and depending from said run, and means to deliver packages singly into position to be engaged and fed forward by said pushers, the combination with said endless chain elements and pushers, of a clamping member associated with each pusher and mounted to swing about a

horizontal axis, and means to swing each clamping member upwardly to pass over a package which has just been delivered to said support, and then to swing said clamping member downwardly into position to clamp said package to the pusher as the latter engages the package to move it forward, said clamping member having a laterally-extending finger to engage the top of the package.

3. In a wrapping machine, the combination with a support on which the packages to be wrapped are supported, of an endless carrier having one run above and parallel to said support and situated above the packages supported thereon, pushers mounted on said carrier and arranged to depend from said run thereof, means to deliver packages singly into position to be engaged by the pushers, the latter operating to move the packages over the support, a clamping member associated with each pusher and adapted to engage the front side of the package engaged by said pusher, each clamping member being mounted to swing about a horizontal axis, a cam device for swinging each clamping member upwardly to pass over a package which has just been delivered to the support, and a spring to swing said clamping device downwardly into clamping engagement with the package after passing the cam.

4. In a wrapping machine comprising a table or support over which packages to be wrapped are moved, an endless chain element having one run operating above said support, pushers carried by said element and depending from said run, and means to deliver packages singly into position to be engaged and fed forward by said pushers, the combination with said endless chain elements and pushers, of a clamping member associated with each pusher and mounted to swing about a horizontal axis, said clamping member having an arm, and a stationarily mounted cam adjacent the point where the packages are delivered to the support and situated to engage said arm whereby each clamping member is swung upwardly into horizontal position to pass over the package, and a spring acting on said clamping member to swing it downwardly into clamping engagement with the package, said clamping member having a laterally-projecting finger to engage the top of the package.

In testimony whereof, I have signed my name to this specification.

HARRY L. JOHNSON.
